FILAMENT COIL FEEDER

Alonzo C. Jones, Hamilton, Ontario, Canada, assignor to Canadian Westinghouse Company, Limited, Hamilton, Ontario, Canada

Application April 18, 1949, Serial No. 88,153

8 Claims. (Cl. 214—1)

1

This invention relates to placing filament coils, as in the manufacture of incandescent electric lamps, one by one in the consecutive notches of a feeding drum, from whence they are to be picked up and fastened to the supports of a mount.

The principal object of my invention, generally considered, is to provide a mechanical device mounted directly adjacent a coil-feeder drum for placing a single coil in each consecutive notch of said drum as it is indexed upon step-by-step rotation.

Another object of my invention is to provide a machine for feeding filament coils one by one, as from a hopper thereof to a notched simultaneously-indexed coil feeding drum, comprising a vacuum finger which picks up a coil, a spring operated stripper member associated therewith to prevent pick-up of more than one coil, a guide on which said coil is deposited, and a gate at the end of said guide for stopping and aligning said coil with a notch of a feed drum indexed directly therebeneath, which gate, upon a return of said finger to pick up the next coil, is opened and said coil dropped in said notch.

A further object of my invention is to provide a method of placing filament coils one by one in consecutive notches of a feeding drum for a mounting machine, comprising picking up a single coil from a hopper by vacuum, while releasing a previously picked-up coil to drop into a notch of said feeding drum, depositing it on a guide leading to said drum, while indexing said drum for the subsequent reception of said coil, stopping said coil at the end of said guide to allow it to be aligned with the indexed drum notch therebeneath, then while picking up the next coil, releasing it to drop in said notch, repeating the operation.

Other objects and advantages of the invention will become apparent as the description proceeds.

In the drawing:

Figure 1 is a fragmentary elevational view, partly in vertical section, of apparatus embodying my invention, the vacuum pick-up finger being shown in position immediately after leaving a coil on the guide behind the feed gate and over an indexed slot in the feed drum.

Figure 2 is a fragmentary plan of the apparatus shown in Figure 1.

Figure 3 is a fragmentary vertical sectional view on the line III—III of Figure 2, in the direction of the arrows.

Figure 4 is a fragmentary vertical sectional view on the line IV—IV of Figure 2, in the direction of the arrows, but showing the feed gate

2

open and the vacuum pick-up finger in a position returned for picking up another coil.

Figure 5 is a detailed axial sectional view of one form of vacuum finger and stripper in coil pick-up position.

Figure 6 is a fragmentary elevational view of the finger, on the line VI—VI of Figure 5, looking in the direction of the arrows.

Figure 7 is a view corresponding to Figure 6, but showing another form of finger.

Figure 8 is a chart showing the relative positions of the parts at the different phases of a cycle.

When feeding filament coils at a rate as high as 1400 per hour, it has proven very difficult for an operator to pick up a coil with a pair of tweezers and place the same in a slot of a filament coil feeding drum, without missing some of the slots, and without improper placement of the coils. I have, therefore, devised a machine which can be mounted adjacent such a feeding drum, and which mechanically picks up filament coils one by one and accurately places them in consecutive notches of said drum.

25 Referring to the drawing in detail, like parts being designated by like reference characters, and first considering the embodiment of my invention illustrated in Figures 1 to 6, inclusive, there is shown a hopper 11 having side walls 12 placed an adjusted distance apart, corresponding with the length of the filament coils 13, a quantity of which are shown deposited therein. Adjustment of the side walls may be effected by connecting them to the hopper bottom wall 10 by screws 20 threaded thereto, and received in slots 30 in said bottom wall. In order to keep the filament coils straight and disposed perpendicular to the longitudinal center line of the hopper, a block 14 is disposed behind said coils, and may be manually advanced as desired in the direction of the arrow 15.

The end of the hopper toward the coil feeding drum 16, mounted for clockwise rotation on shaft 35 and provided with coil-receiving notches 45 17, has a wall 18 preferably sloping as indicated and formed with a slot 19. In this slot moves a vacuum pick-up finger 21, mounted on hollow shaft 22, which is in turn pivoted in base or bearing block 23, supported on brackets 40.

50 There is also provided a stripper element 24 pivoted about a fixed shaft 25 and urged into engagement with the vacuum finger 21, when the latter engages it, as in Figure 4, by means of a coil spring 26 disposed between said stripper and an abutment 27 on the shaft 25.

Bridging the distance between the hopper 11

and the drum 16, are desirably curved guide members 28, forming a guide on which the coils are deposited one by one, and down which they slide toward the drum 16. The guide members 28 are spaced to leave a slot 29 therebetween, as a continuation of the slot 19, and in which the finger 21 moves. The upper surface of said guide which supports each coil is such that it lies below the filament-receiving notch 31 in the finger, until after said finger has reversed so that the notch opens upwardly, whereupon the guide is such that the coil is lifted out of said notch, and from there slides to the end of said guide where it is stopped by a feed gate 32 pivoted at 33 and carrying an operating arm 34.

In order to insure that the pick-up arm 21 exerts the desired action on the coils 13, it is cored hollow, as indicated at 36, to the slot 31, which is of the proper size for picking up a single coil. That is, the slot 31 is of a width and depth corresponding with the coil diameter plus a tolerance of about .004". The hollow portion of the pick-up arm 21 is connected to a vacuum line 37 by an opening from said hollow portion 36, through the hollow center 38 of the shaft 22, and through a slot 39 which when said shaft is in picking-up position is turned to register with a port 41 in the bearing block or base portion 23, with which the vacuum line 37 directly communicates.

In order to insure that the pick-up arm 21 is cleaned of any dust or debris after each pick-up action on a coil, a compressed air line is also desirably connected to the hollow center 38 of the shaft 22 at the end thereof, as shown most clearly in Figure 1, and a valve 43 is provided in the compressed air line which, when opened as shown in full lines in Figure 1, allows air to pass through said line 42, through the hollow center 38 of the shaft 22, on through the hollow 36 in the finger 21, and out through the slot 31 in said finger, to thereby insure that it is cleaned prior to picking up another coil.

The means for turning the shaft 22 and swinging the attached finger 21, in the present embodiment involves a gear wheel 43 fixed on the shaft 22 and engaged by a rack 44. The latter is slidably guided in an extension 45 from the bearing block 23, and reciprocated through a connecting rod 46, one end of which is pivoted thereto as at 47 and the other end of which is pivoted to an arm 48 of a bell crank lever 49, as indicated at 51. The bell crank lever is in turn pivotally mounted on a fixed bracket 52, as indicated at 53, and has another arm 54 desirably carrying a roller 55, pivoted thereto as at 56, and urged, as by gravity or spring means, into operative engagement with a cam 57 turned by a drive shaft 58.

The arm 54 of the bell crank lever 49 carries an adjustable element, such as a stud 59, threaded into an angular extension 61, and held in desired position by means of lock nuts 62. The stud 59, after proper adjustment, at the appropriate times engages valve 43 for connecting the compressed air supply to the hollow shaft 22. The feed gate 32 is opened at the proper times to allow a filament coil therebehind to drop into an indexed notch 17 in the feed drum 16 therebelow, by cam 63 fixed on shaft 22, and engaging the operating arm 34.

In order to insure that the notches 17 in the drum 16 are synchronously indexed beneath the end of the guide 28 at the proper times for the reception of coils therefrom, said drum is driven

5 step-by-step from the same shaft 58 from which the rack 44 is driven, as by means of another cam 64 on said shaft and engaging a roller 65 pivoted, as indicated at 66, to an arm 67, urged into engagement with said cam by gravity or spring means. The arm 67 is part of a bell crank lever 68 pivoted on the shaft 35 of the drum 16, and carrying a pawl 69 on its other arm 71. The pawl 69 is pivoted to said arm 71 as indicated at 72, and urged by spring 73 into operative engagement with a ratchet wheel 74 secured to the drum 16 and movable therewith about the shaft 35. Means, such as a ratchet-engaging pawl 75, pivoted to a fixed part of the apparatus, is provided to prevent undesired rotation of the drum 16.

20 Referring now to the embodiment of my invention illustrated in Figure 7, there is shown another design 21^a of a pick-up finger, which is formed hollow as indicated at 36^a, and generally like the finger 21, but instead of terminating in a single aperture 76 to the pick-up slot 31, as in Figures 5 and 6, is formed with two apertures 76^a which thereby hold a coil in said slot at two points rather than one point.

25 The mode of operation of the aforescribed apparatus is normally as follows, reference being had to Figure 8: A quantity of coils 13 are placed in the hopper 11 and backed up by the block 14 so that they lie transverse of said hopper without being tangled. The machine, on starting, causes the finger 21 or 21^a, as the case may be, to move counterclockwise through the slots 29 and 19, finally engaging the stripper member 24 which slides thereover and is moved thereby, from the position of Figure 3 to that of Figure 4. This means that after the reception of a single coil in the notch 31 or 31^a, as the case may be, any other coils are brushed off by the stripper element 24, before the finger advances out of the hopper 11 from the position of Figure 4 toward that of Figure 3.

30 When in the position of Figure 4, it is connected to the vacuum line 37 through the port 41, slot 39, hollow 38 in the shaft 22, and hollow 36 in the finger itself, thereby insuring that sufficient suction is applied to hold a coil in the pick-up notch until, by movement of the rack 44 upon appropriate turning of the cam 57, the coil is moved to a position above the guide 28. As the finger 21 or 21^a passes below the top outline of said guide to the position of Figure 3, the coil is deposited thereon and slides therewith to the position indicated in Figure 3. Here it is stopped by the feed gate 32, then in closed position by virtue of the cam 63 not being in position to push on the arm 34 and open said gate. After release of the coil, the valve 43 is opened by the element 59 and the pick-up finger blown out by compressed air.

35 Further turning of the cam 63, however, on return of the pick-up finger, causes its high dwell 78 to engage said arm 34 and open the gate 32, holding it in the position of Figure 4, while the finger picks up the next coil, as shown in said figure. Whereupon the coil behind the gate 32 is dropped into the slot 17 indexed therebeneath. This indexing was effected between the coil pick-up operation and the release of the coil on the guide 28, by corresponding movement of the drum, one tooth of the ratchet 74 of which corresponds in angular distance with one notch of the drum 16, by simultaneous turning of the cam 64 on the shaft 58. The operation continues with the moving of the picked-up coil over the guide 28, the

dropping of it on said guide behind the gate 32, and the eventual release of said gate upon the return of the finger for still another coil.

Although a preferred embodiment of my invention has been disclosed, it will be understood that modifications may be made within the spirit and scope of the appended claims.

I claim:

1. A machine for moving coils from a quantity thereof and placing them one by one in consecutive indexed notches of an indexing notched feeding drum, comprising a guide above the drum and bridging the space between it and said coils, a vacuum pick-up finger with a notch just the right size for the reception of only one coil, a bearing block, a vacuum connection to said block, a hollow shaft pivoted in said block, formed with a slot connecting its interior with said vacuum connection when said shaft is in certain angular positions in said block, a gear wheel fixed on said shaft, and means for oscillating said gear wheel to cause said finger to engage said coils, pick up one therefrom, and deposit it on said guide to allow it to drop into an indexed notch in the feeding drum therebeneath.

2. A machine for moving coils from a quantity thereof and placing them one by one in consecutive indexed notches of a feeding drum, comprising a guide bridging the space between said coils and said drum therebeneath, a vacuum pick-up finger with a notch just the right size for the reception of only one coil, whereby said finger may pick up a coil and move it to said guide for transfer to said drum, a slidably mounted member for oscillating said finger, a bellcrank lever pivoted beneath said guide, one arm of said lever being operatively connected to said member for reciprocating the same, a drive shaft adjacent said lever, and a cam on said shaft engaging the other arm of said lever for effecting oscillation thereof.

3. A machine for moving coils from a quantity thereof and placing them one by one in consecutive indexed notches of a feeding drum, comprising a guide bridging the space between said coils and said drum therebeneath, a vacuum pick-up finger with a notch just the right size for the reception of only one coil, a bearing block, a vacuum connection to said block, a hollow shaft for completing the vacuum connection to said finger and on which said finger is mounted, means for oscillating said finger through said shaft, a compressed-air connection through said hollow shaft to said finger, a valve in the compressed air line, and an adjustable element carried by the means operating said finger for opening and closing said valve at the proper times in synchronism with the finger movement.

4. Apparatus for feeding coils from a quantity thereof and placing them one by one in consecutive indexed notches of a feeding drum, comprising a guide bridging the space between said coils and said drum therebeneath, a vacuum pick-up finger with a notch just the right size for the reception of only one coil, a bearing block, a vacuum connection to said block, a hollow shaft pivoted in said block for completing the vacuum connection with said finger, means for oscillating said finger between pick-up and releases positions, a feed gate pivoted so as to normally close the end of the guide and hold a coil deposited on said guide, an arm carried by said gate, and a cam on said hollow shaft engageable with said arm so as to open said gate at the proper times and release a coil

from said guide, for placing it in an indexed notch in said feeding drum.

5. Apparatus for feeding coils one by one for mounting, comprising a hopper in which a quantity of said coils are deposited, a shaft, a notched feeding drum mounted on said shaft, a curved guide extending from the adjacent end of said hopper to said drum, and means for moving coils from said hopper and placing them one by one in consecutive indexed notches in said drum, comprising a hollow vacuum pick-up finger with a notch just the right size for the reception of only one coil, a bearing block, a vacuum connection to said block, a hollow shaft pivoted in said block, formed with a slot connecting its interior with said vacuum connection when said shaft is in certain angular positions in said block, said shaft carrying and communicating with said finger, a gear wheel fixed in said shaft, a slidably rack meshing with said wheel, means beneath said guide for reciprocating said rack, a drive shaft adjacent said means, a cam on said drive shaft engaging said operating means and reciprocating said rack at the proper times, means movable over said finger to remove any coil not in said notch, another cam on said shaft, a bellcrank lever pivoted on the drum shaft, one arm of said lever being engaged by said other cam and the other arm of said lever carrying a spring-actuated pawl, said drum carrying a ratchet engaged by said pawl, a connection to said hollow shaft for supplying compressed air to said finger, a valve in the compressed air connection, and means for opening and closing said valve at the proper times in synchronism with movement of said finger.

6. Apparatus for feeding coils one by one for mounting, comprising a hopper in which a quantity of said coils are deposited, a shaft, a notched feeding drum mounted on said shaft, a curved guide extending from the adjacent end of said hopper to near said drum, and means for moving coils from said hopper and placing them one by one in consecutive indexed notches in said drum, comprising a hollow vacuum pick-up finger with a vacuum-communicating notch just the right size for the reception of only one coil, a bearing block, vacuum connection to said block, a hollow shaft pivoted in said block, formed with a slot connecting its interior with said vacuum connection when said shaft is in certain angular positions in said block, disposed beneath said guide and carrying said finger, a gear wheel fixed on said shaft, a slidably-mounted rack meshing with said wheel, a bell-crank lever pivoted beneath said guide, one arm of said lever being operatively connected to said rack for reciprocating the same, a drive shaft adjacent said lever, a cam on said drive shaft engaging the other arm of said lever for reciprocating said rack at the proper times, a spring-actuated stripper slidably movable over said finger to remove any coil not in said notch, another cam on said shaft, a second bell crank lever pivoted on the drum shaft, one arm of said second lever being engaged by said other cam, the other arm of said second lever carrying a spring actuated pawl, said drum carrying a ratchet engaged by said pawl, a compressed air connection to said hollow shaft for supplying air to said finger, said shaft communicating with said hollow finger, a valve in the compressed air line, an adjustable element carried by the first mentioned lever for opening and closing said valve at the proper times in synchronism with the movement

of said finger, a feed gate pivoted so as to normally close the end of, and hold a coil when deposited on, said guide, an arm carried by said gate, and a cam on the hollow shaft engageable with said arm, so as to open said gate at the proper times and release a coil from said guide for placing it in an indexed notch in said feed drum.

7. Apparatus for transferring coils from a quantity thereof and placing them one by one in consecutive indexed notches of a feeding drum, comprising an inclined guide bridging the space between said coils and said drum, means for picking up one coil at a time and placing it on said guide, a feed gate pivoted so as to normally close the end of the guide and hold a coil deposited thereon, an arm carried by said gate, and a cam engageable with said arm so as to open said gate at times, synchronized with the movement of said drum, for placing a coil in an indexed notch of said drum.

8. Apparatus for feeding coils one by one from a hopper thereof to a notched feeding drum, comprising an inclined guide extending from the adjacent end of said hopper to said drum, 25

a shaft on which said drum is mounted, means for moving coils one by one from said hopper and placing them on said guide, comprising a drive shaft, a cam on said drive shaft engaging operating means for said coil-moving means, another cam on said drive shaft, a bell-crank lever pivoted on the drum-mounting shaft, one arm of said lever being engaged by said other cam, the other arm of said lever carrying a spring-activated pawl, and said drum carrying a ratchet engaged by said pawl.
